HAIR COMB

Emile Liebert, Los Angeles, Calif.

Application July 9, 1948, Serial No. 37,903

1 Claim. (Cl. 132—23)

1

This invention relates to a hair comb of the type for holding hair in place and has for its primary object to provide a comb that will effectively grip the hair to minimize any tendency to slip from its set position.

Another object of the present invention is to provide a comb in which fixed and relatively movable teeth cooperate to grip hair to, thereby, insure non-slipping application of the comb.

Another object of the invention is to provide a comb of the character above referred to that has two sets of oppositely urged movable teeth that simultaneously move, after manual separation, toward the fixed teeth to grip hair for the purpose intended.

The invention also has for its objects to provide such means that are efficient in operation, convenient in use, economical of manufacture, relatively simple, and of general superiority and serviceability.

The invention also comprises novel details of construction and novel combinations and arrangements of parts, which will more fully appear in the course of the following description of a preferred embodiment of the invention.

In the drawing:

Fig. 1 is a front elevational view, partly broken away, of a comb embodying features of the present invention.

Fig. 2 is a vertical cross-sectional view as taken on line 2—2 of Fig. 1.

Fig. 3 is a transverse sectional view as taken on line 3—3 of Fig. 1.

Fig. 4 is a fragmentary front view showing the comb with the movable teeth separated from the fixed teeth.

The embodiment of the invention that is illustrated comprises, generally, a main body part 5 that is formed to have a spine or back 6 and unitary or integral teeth 7, symmetrically arranged elements 8 each of which comprises a strip 9 and integral teeth 10 mounted on the back 6, manual means 11 for effecting movement of elements 8 to separate the teeth 10 thereof from teeth 7, spring means 12 for effecting automatic return of the teeth 7 and 10 to hair gripping contiguity, and a cover plate 13 for the front face of the back.

Except for the spring means 12 which are preferably of metal, the other components of the comb may be made, as desired, of metal, plastic, bone, wood, or other suitable materials or combinations of materials. These components may be die-formed, molded or cast according to specific desired results.

2

The back 6 of the body part 5 may be curved as shown and, longitudinally, is provided with a channel 14 that extends between end abutments 15 and vertically is defined by a wall 16 and upper ends 17 of the fixed teeth 7.

The strips 9 of elements 8 reside in channel 14, one on each side of the middle thereof and are of such length they and the teeth 8 thereon may move endwise as limited by abutments 15. The 10 spring means 12 are interposed between said abutments and recesses 18 formed in adjacent ends of strips 9 to urge elements 8 toward each other and, thereby, urge the movable teeth 10 into contiguity to the fixed teeth 7.

15 The means 11 is shown as a member having sliding engagement in a slideway 19 formed in back 6 above channel 14 and intersecting the same. Said member is formed with a normally protruding part 20 at its outer end and with a wedge part 21 at its inner end for wedging engagement with chamfered edges 22 provided on adjacent portions of strips 9. It is evident, therefore, that, upon manual depression on part 20 of means 11, elements 8 will be separated from the position of Fig. 1 to that of Fig. 4, and that, upon release of means 11, spring means 12 will return said elements to their initial position and, thereby, re-project means 11.

The teeth 7 and 10, except for the end teeth 30 1a on the body 5 and the inner teeth 10a on elements 8, are arranged as cooperating pairs as best seen in Fig. 1. Accordingly, each of the teeth 7 and 10 is provided with a flat side 23 and the sides of said pairs of teeth so interfit that each pair comprises a single tooth. Thus, the 35 present comb may be drawn through the hair in the manner of a conventional comb.

The teeth 7 and 10 may, of course, be straight, in which case it may be desired to roughen or 40 knurl the faces 23 to improve the grip between cooperating teeth. Or, as shown, the teeth may have a sinuous or serpentine form to improve resistance to outward displacement of the comb when gripping hair. In any case, the spring 45 means 12 are provided with sufficient force to cause a firm yet resilient gripping of the hair by the cooperating teeth to insure against displacement of the comb and possible loss thereof.

The cover plate 13 encloses channel 14 to hold 50 elements 8, means 11 and springs 12 in operative position and may be secured to back 6 in various ways.

In use, the comb back is held in one hand with a finger depressing means 11 to effect separation 55 of the teeth. The comb is applied where wanted.

The means 11 is then released and the teeth grip the hair as herein above indicated.

While I have disclosed what I now regard as the preferred embodiment of my invention and since the construction is capable of modifications within the spirit and scope of my invention, I do not wish to restrict myself to the particular form of construction illustrated and described, but desire to avail myself of all modifications that may fall within the scope of the appended claim.

I claim:

A hair comb comprising a main body part formed to have a back and fixed teeth, said back having a longitudinal channel therein, a pair of similar elements mounted in said channel one on each side of the middle of the back and each having teeth in operative engagement with the fixed teeth, resilient means for urging said elements toward each other to effect contiguity of

the fixed teeth and the teeth on the elements, and manual means for separating the elements and thereby separating the fixed teeth from the teeth on the elements, said latter means comprising a wedge member movable transversely to said channel and engaged with the elements to spread them.

EMILE LIEBERT.
